US00D876008S

(12) **United States Design Patent** (10) **Patent No.:** **US D876,008 S**
Cheung et al. (45) **Date of Patent:** **** Feb. 18, 2020**

(54) **CASE**(71) Applicant: **JUUL Labs, Inc.**, San Francisco, CA (US)(72) Inventors: **Brandon Cheung**, San Francisco, CA (US); **Richard Johnson**, San Francisco, CA (US); **Kevin Lomeli**, San Francisco, CA (US); **James Monsees**, San Francisco, CA (US); **Alexander Ringrose**, San Francisco, CA (US); **Roxolana Wacyk**, San Francisco, CA (US)(73) Assignee: **JUUL Labs, Inc.**, San Francisco, CA (US)(**) Term: **15 Years**(21) Appl. No.: **29/660,806**(22) Filed: **Aug. 22, 2018****Related U.S. Application Data**

(63) Continuation of application No. 29/638,723, filed on Feb. 28, 2018.

(51) **LOC (12) Cl.** ..... **27-06**(52) **U.S. Cl.**USPC ..... **D27/186**(58) **Field of Classification Search**

USPC D27/100, 101, 161, 162-194; D23/366; D24/110; D19/101, 106, 115, 165, 195

CPC A24F 47/00; A24F 47/002; A24F 15/12

See application file for complete search history.

(57)

CLAIM

The ornamental design for a case, as shown and described.

DESCRIPTION

FIG. 1 is a front, right side, and bottom perspective view of a case of our design;

FIG. 2 is a front, right side, and top perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is a cross-sectional view thereof, taken along the line 9-9 as shown in FIG. 3.

The dash-dash broken lines illustrate portions of the case that form no part of the claimed design.

1 Claim, 9 Drawing Sheets# US D876,008 S
